SEALING STRIP FOR THE SLIDING ROOF OF A
VEHICLE OR SIMILAR ARTICLE

Harry Edwards, Solihull, England, assignor to Weather-
shields Limited, Birmingham, England

Filed June 30, 1970, Ser. No. 23,760

Claims priority, application Great Britain Dec. 31, 1969

Term of patent 14 years

Int. Cl. D12—16

U.S. Cl. D14—6

FIG. 1 is a perspective view of the front and one end from above of a sealing strip for the sliding roof of a vehicle showing my new design;

FIG. 2 is a section on line 2—2 of FIG. 1;

FIG. 3 is a plan view of the strip;

FIG. 4 is an underneath plan view of the strip;

FIG. 5 is a front elevation thereof, and

FIG. 6 is a rear elevation of the strip.

The strip is of indeterminate length and of constant cross-section throughout.

I claim:

The ornamental design for a sealing strip for the sliding roof of a vehicle or similar article, as shown and described.
